UNITED STATES PATENT OFFICE.

HENRY B. FISCHER AND CHARLES H. FISCHER, OF CINCINNATI, OHIO.

BOTTLE-WASHER.

SPECIFICATION forming part of Letters Patent No. 605,180, dated June 7, 1898.

Application filed November 15, 1897. Serial No. 658,530. (No model.)

To all whom it may concern:

Be it known that we, HENRY B. FISCHER and CHARLES H. FISCHER, citizens of the United States, and residents of Cincinnati, Hamilton county, State of Ohio, have invented a certain new and useful Bottle-Cleaning Device; and we do declare the following to be a clear, full, and exact description of the invention, such as will enable others skilled in the art to which it appertains to make and use the same, attention being called to the accompanying drawings, with the reference-numerals marked thereon, which form a part of this specification.

This invention relates to an apparatus for cleaning and washing bottles and whereby they are first scoured for the purpose of loosening and removing the more solid substances adhering to the glass, after which they are rinsed and washed out to remove these substances as well as any remaining parts of the scouring medium which is used. This latter is preferably sand or any other material having a similar action when used, as hereinabove described. Water is the other medium used, first in connection with the scouring medium and then alone for rinsing purposes. The object is to provide a practical and simplified construction for applying these media first together and then the water alone. As against a similar apparatus for the same purpose and described in our allowed application, serially numbered 626,205, the construction here shown is still more simplified and a number of parts are dispensed with, whereby the manufacturing cost is correspondingly reduced and the action and operation improved.

In the following specification and particularly pointed out in the claims is found a full description of the invention, its use, operation, and construction, which latter is also illustrated in the accompanying drawings, in which—

Figure 1 shows in a central vertical section the apparatus complete and in operation. Fig. 2 is an elevation of the same. Fig. 3 is a top view of it, showing it operating upon a flat bottle. Fig. 4 is a horizontal section on line 4-4 of Fig. 1. Fig. 5 is an enlarged section on line 5-5 of Fig. 1. Fig. 6, in an elevation, shows several of the devices arranged in series.

Sand is preferably used in this case as a

scouring medium and water as a carrier for it, whereby the same is thrown against the interior surfaces of the bottle, loosening and removing by its impact as well as frictional contact any impurities thereon. After this combined action of sand and water the latter is used alone for rinsing and flushing purposes, whereby the bottle is washed out, removing the loosened impurities as well as the sand previously used. In prior devices of this kind and for the same purpose it has been customary to use two independent pipes, one conveying the scouring-current (sand and water) and the other conveying the rinsing or flushing current—that is, water alone—the action of one being interrupted during activity of the other. This arrangement had been simplified in our allowed application, previously referred to, to the extent of using in part one pipe only for the two currents, and in this present application it is still more simplified by using altogether only one pipe, which alternately conveys the scouring as well as the flushing current and whereby no duplicate parts are used, such as were previously required for independent conveyance of the two currents through separate pipes. In the drawings this pipe is indicated by 8 and provided with an upper part forming a discharge-nozzle 9, which is preferably separable to permit interchange with lower or higher ones to suit the height and size of the bottle to be cleaned. These latter are supported in an inverted position above the discharge-nozzle, with this latter preferably reaching into the neck of the bottle, but with sufficient space below the bottom of the latter to permit the discharged current to spread, which is necessary to obtain the proper effect. Pipe 8 is supplied from a pipe 11, which may be a service-pipe of a waterworks system, where such is obtainable, since sufficient pressure is required to cause the water to discharge and reach the bottle with requisite force when the same is placed in a position above pipe 8, as shown, for instance, in Fig. 1. Pipe 8 is surrounded by a cup or bowl shaped vessel 13 and has its wall pierced by one or more lateral holes 14, located at such a height as to communicate with the lower part of vessel 13. This latter contains the scouring medium—sand in this case—which lies around these openings, so that water passing up through pipe 8 an injector or siphon like ac-

tion takes place, whereby the sand is sucked in through these openings and carried up with the water. A part of pipe 8 below openings 14 is contracted, as shown at 15, so that the water is ejected in form of a jet, which does not completely fill the upper part of the pipe, thereby providing room for the entering sand and improving the action. This scouring-current, combined of water and sand, strikes first 10 the bottom inside the bottle, after which it spreads and passes down on the inside thereof and scours by its contact the bottle thoroughly. After this action of the scouring-current has been maintained a sufficient length 15 of time, contingent, of course, on the condition of the bottle, a few seconds, however, being sufficient in most cases, then its action is discontinued and a current of clear water injected, which issues from the same discharge- 20 nozzle and also strikes against the bottom of the bottle, where it spreads and running down on the sides thereof removes all previously-loosened impurities as well as any remaining sand and thoroughly flushes the bottle out. 25 In order to obtain this flushing-current, holes 14 in pipe 8, which admit the sand, are closed, for which purpose a lid or cover 16 is provided for each, which is so supported and connected with means for operation as to be conveniently 30 accessible from the outside to permit opening of these lids when the scouring-current is required and closing of them when the flushing-current is wanted.

When the device is not used or while changing bottles, the water is shut off from pipe 11 in any suitable manner—as, for instance, by a stop-cock. During this latter operation it is preferable, however, not to shut off the water entirely, but to maintain the escape of a small 40 current of it sufficient to prevent any sand from packing into the contracted passages at 15.

In order to reach the corner between side and bottom of a bottle when shaped as shown 45 in Fig. 1, the discharging currents are caused to assume a direction accordingly. This may be done, as shown in Fig. 1, by supporting a cone-shaped plug 10 in inverted position above the discharge-opening, or, as shown in Fig. 6, 50 by having a tip 12 at the end of the pipe, which is bored at an angle to the bore of the pipe, thereby changing the direction of the discharge from the latter. Since in the case of such a tip being used the current from of 55 strikes only in one place, rotation of it or of the bottle becomes necessary to reach all parts of the latter. The bottle may be rotated by taking hold of it and moving it around on the bottle-supports; or the tip may be caused 60 to rotate, which rotation may be automatic by means of the discharging current. For such purpose the tip is loosely mounted so as to be free for rotation and its outlet formed on a line passing at the same time through 65 two different planes. At a in Fig. 6 that direction of the bore is shown, which is given it for the purpose of changing the direction of

the current. At b the same bore is shown as it is curved at the same time in another plane for the purpose of causing the tip to rotate by 70 the reactive force of the discharging current. Catch-springs 20 are provided to prevent the tips from being lifted off by the force of the current.

To prevent splashing of the water which 75 discharges from the bottle, the height of vessel 13 is increased, which, for convenience of construction, is done by a superposed cylindrical member 17. Overflow-openings 18 are provided in this latter, through which the surplus water and any floating impurities pass 80 out, while the sand settles to the bottom of vessel 13, to be used again. The overflowing water is caught in an annular gutter 19, from which it drains off through waste-pipe 21. 85

To prevent the water which discharges out of the mouth of the bottle from running straight down on pipe 8, where it would wash the sand away from openings 14, a spreader 22 is provided, suitably supported, which 90 causes the water to descend near the sides of vessel 13, whereby the sand is given a tendency to accumulate in the center of the latter, where it piles around pipe 8 and holes 14 therein. 95

To prevent any of the water shed over the outer edge of spreader 22 from splashing through the overflow-openings, where it would gradually carry the sand away, a guard 23 is provided in front of the latter—that is, with reference to the flow—and inside of which the water passes down. This guard is substantially an annular ring supported within member 17 and formed by the lower part of another cylindrical member 24, slipped into 100 member 17 and provided with a bead 25, whereby it rests upon the upper edge of the latter. It is also extended upwardly above this bead, thus also adding to the height of vessel 13. Near the upper end of this structure—that is, on member 24 when built up as described— 105 are provided the bottle-supports 26, upon which the bottle rests while being scoured and flushed. They are arranged and constructed to support bottles of the usual shapes 110 as they occur—that is, round or square, as shown in Figs. 1 and 2, or flat, as shown in Figs. 3 and 6. They are preferably made of spring-wire, shaped as shown and secured in 115 sockets 27 on the outside, from which they extend up and into the upper end of the device. Their inner ends are preferably left 120 disconnected, so as not to interfere with their spring action, permitting them to yield more or less when the bottles are placed between 125 them.

For opening and closing apertures 14 their lids 16 have a swinging movement to and from them, which is preferable to a sliding one, since it obviates friction and cutting of 130 metal surfaces in case any sand-grains are caught between. For such purpose each lid is mounted on a lever 28, pivotally supported at 29 and provided with a spring 31 to keep

them normally closed. To open them, means should be used whereby all may be operated simultaneously, for which purpose we provide a cam-plate 32, having slots 33 occupied by the upper ends of levers 28 and so shaped and located as to move the levers upon rotation of the plate. This cam-plate is preferably supported upon a shoulder on pipe 8 and held in place by a nut 30 above it. A handle 34 is extended from the plate to the outside for such rotation. At the inner ends of cam-slots 33 flat places are provided in their curves, as shown at 35, which when entered by the ends of levers 28 cause the cam-plate to remain in such position—that is, for holding openings 14 open—without requiring it to be held so by the hand on handle 34. To obviate or reduce friction, the upper ends of levers 28, which occupy slots 33, should be provided with rollers. Where more than one of these devices are used, they may all be mounted upon or connected to one supply-pipe 11. They should all operate together, for which purpose all handles 34 are connected by a rod 36, which latter is then provided with the operating-handle 37. (See Fig. 6.) One drain-gutter 38 and one waste-pipe 21 may also be used for the whole series. 30 Where the devices are not connected to or above a sink, a suitable base 39 may be provided.

Having described our invention, we claim as new—

- 35 1. In a bottle-cleaning device, the combination of a vessel to contain the scouring medium, a water-pipe passing through the same, having lateral openings which communicate with the lower part of the vessel, means to open and close these openings and supporting means for holding an inverted bottle above the discharge end of the water-pipe.
- 40 2. In a bottle-cleaning device the combination of a vessel 13 a water-pipe 8, lateral openings 14 therein, lids 16 for these openings means to open and close them and a support for holding an inverted bottle above the water-pipe.
- 45 3. In a bottle-cleaning device, the combination of a vessel 13 a water-pipe 8, lateral openings 14 therein, lids 16 for these openings levers 28 which carry these lids, means to swing the levers for closing or uncovering openings 14 and a support for holding an inverted bottle above the water-pipe.
- 50 4. In a bottle-cleaning device, the combination of a vessel 13 a water-pipe 8, lateral openings 14 therein, lids 16 for these openings, levers 28 which carry these lids, a cam-plate 32 with an accessible handle for operating these levers to open or close openings 14 and a support for holding an inverted bottle above the water-pipe.
- 55 5. In a bottle-cleaning device the combination of a vessel 13, a water-pipe 8, lateral openings 14 therein, lids 16 for these openings means to open and close them, a spreader

22 supported on pipe 8 and a support for holding an inverted bottle above the water-pipe.

6. In a bottle-cleaning device, the combination of a vessel 13 a water-pipe 8 having lateral openings 14, a member 17 superposed upon vessel 13 to add to the height of the latter and provided with overflow-openings 18 and a support for holding an inverted bottle 75 above the water-pipe.

7. In a bottle-cleaning device, the combination of a vessel 13, the height of which is increased by the superposition of additional members fitted thereto, a water-pipe 8 having lateral openings 14, and the curved spring-wire bottle-supports 26 projecting upwardly and turned over the uppermost member and extending downwardly within the same.

8. In a bottle-cleaning device, the combination of a vessel 13, a water-pipe 8 having lateral openings 14, a member 17 superposed upon vessel 13 to add to the height of the latter and provided with overflow-openings 18 an annular drain-gutter 19 with waste-pipe 90 21 below them and a support for holding an inverted bottle above the water-pipe.

9. In a bottle-cleaning device, the combination of a series of vessels 13, a water-pipe 8 for each, a supply-pipe 11 for all these water-pipes, lateral openings in these latter, means to open and close them, a connecting-rod attached to these means in a manner to cause all of them to operate together, and bottle-supports above each vessel.

10. In a bottle-cleaning device, the combination of a series of vessels 13, a water-pipe for each, a supply-pipe 11 for all these water-pipes, lateral openings 14 in these latter, bottle-supports above each vessel, a superposed member 17 on each of the latter to increase their height overflow-openings in them and a drainage-gutter with waste-pipe surrounding the whole series of vessels below the overflow-openings in the latter.

11. In a bottle-cleaning device the combination of a vessel adapted to contain the scouring medium, a water-pipe communicating with the same, supporting means for holding an inverted bottle above the discharge end of the water-pipe and a tip on this latter so mounted as to be capable of being rotated by the force of the discharging current.

12. In a bottle-cleaning device, the combination of a vessel 13, a water-pipe 8 having lateral openings 14, a member 17 superposed upon vessel 13, to add to the height of the latter and provided with overflow-openings 18, a guard 23 interposed in front of them and a support for holding an inverted bottle above the water-pipe.

In testimony whereof we hereunto affix our signatures in presence of two witnesses.
